UNITED STATES PATENT OFFICE.

ANNA M. LATHAM, OF PORTLAND, MAINE.

DESIGN FOR A FORK.

40,670.

Specification for Design.

Patented May 3, 1910.

Application filed June 24, 1909. Serial No. 504,177. Term of patent 7 years.

To all whom it may concern:

Be it known that I, ANNA M. LATHAM, a citizen of the United States, residing at Portland, in the county of Cumberland and State of Maine, have invented a new, original, and ornamental Design for Forks, of which the following is a specification, reference being had to the accompanying drawing, forming part thereof.

In the drawings the figure shows a plan view of my fork in which the essential features are, in combination with the inverted ear of corn, a representation of a corn stalk, laden with ears of corn upon the handle of

the fork and two rows of connecting pieces between the prongs of the fork, one row being composed of pieces having their edges curved and the other two being formed of pieces tapered to a point at their lower edges:

I claim:

The ornamental design for a fork as shown and described.

ANNA M. LATHAM.
